UNITED STATES PATENT OFFICE.

WILLIAM W. DINGEE, OF RACINE, WISCONSIN, ASSIGNOR TO THE J. I. CASE THRESHING MACHINE COMPANY, OF SAME PLACE.

DESIGN FOR A SEPARATOR-SIEVE.

SPECIFICATION forming part of Design No. 28,987, dated July 5, 1898.

Application filed May 9, 1898. Serial No. 680,228. Term of patent 7 years.

To all whom it may concern:

Be it known that I, WILLIAM W. DINGEE, a resident of Racine, in the county of Racine, State of Wisconsin, have invented and produced a new and original Design for Separator-Sieves, of which the following is a specification, reference being had to the accompanying drawings, forming a part thereof.

Figure 1 is a plan view of a sieve, showing my new design. Fig. 2 is an enlarged sectional view taken on line $x-x$ of Fig. 1. Fig. 3 is an enlarged sectional view taken on line $y-y$ of Fig. 1.

As shown in the accompanying drawings, the leading feature of my design consists of a separator-sieve the body A whereof is formed with ribs or corrugations a extending

lengthwise thereof, each pair of corrugations inclosing plural rows of perforations a' , there being formed at each perforation a flat offset 20 lip a^2 . The flat lips a^2 have parallel edges and circular ends and extend at an angle to the plane of the body A of the sieve, and around the entire body of the sieve extends a suitable border C. 25

Having described my invention, what I claim as new, and desire to secure by Letters Patent, is—

The design for a separator-sieve, as herein shown and described.

WILLIAM W. DINGEE.
